CLAIM

The ornamental design for a barware, as shown and described.

DESCRIPTION

FIG. 1 is a perspective view of the barware showing my new design.

FIG. 2 is a top view of the barware of FIG. 1;

FIG. 3 is a bottom view of the barware of FIG. 1;

FIG. 4 is a front view of the barware of FIG. 1;

FIG. 5 is a rear view of the barware of FIG. 1; and,

FIG. 6 is a side view of the barware of FIG. 1.

The broken lines are for illustrative purposes only and form no part of the claimed design.

1 Claim, 2 Drawing Sheets(56)
